UNITED STATES PATENT OFFICE.

JAMES WILSON LOWTHORP, OF LAWRENCEBURG, TENNESSEE.

DISHWASHER.

Application filed February 17, 1927. Serial No. 169,057.

This invention relates to dishwashers and aims to provide a device so constructed that dishes may be placed therein and thoroughly sprayed to wash, cleanse and sterilize the same.

An important object of the invention is to provide a device of this character including a pump having communication with the interior of the container or body portion of the device so that upon operation of the pump, the liquid in the container may be drawn into the pump and forced into the container in a fine spray, to accomplish the purpose of the invention.

15 A still further object of the invention is the provision of a rack for supporting dishes within the container in such a way that the surfaces of the dishes to be cleaned will be supported directly in front of the openings 20 through which the fluid is sprayed.

25 Still another object of the invention is to provide a rack of this character which may be readily and easily removed so that larger articles such as bowls, churning or the like may be supported over the discharge end of the spray pipe, for cleansing purposes.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 35 within the scope of what is claimed, without departing from the spirit of the invention.

Referring to the drawings:

Figure 1 is a longitudinal sectional view 40 through a dishwashing machine constructed in accordance with the invention.

Figure 2 is a plan view of the machine, the cover being removed.

Figure 3 is a transverse sectional view with the rack and bottom removed.

45 Figure 4 is a fragmental sectional view through the valve housing and valves.

Referring to the drawings in detail, the reference character 5 designates the body portion or container, which is preferably circular in cross section, however, the size and shape of the device may be varied to meet various requirements of use.

50 This container 5 is supported by means of the legs 6 which are formed at the ends of the bars 7 that are in turn secured to the bottom of the container 5 as clearly shown by

Figure 1 of the drawings. Within the container 5 and secured to the inner surface thereof, are bracket members 8 that have inwardly extended end portions 9 defining 60 rests for the removable bottom 10, which is of a construction to closely fit within the container. These inwardly extended end portions of the brackets are arranged in spaced relation with the bottom 11 of the container 65 defining a space at the bottom of the container for containing water to be forced through the spray pump by the pump to be hereinafter more fully described.

The removable bottom 10 is formed preferably of wire mesh material and acts as a support for the dish rack 12 that embodies a lower circular portion 13 and an upper circular portion 14, the portion 14 being substantially small, while the portion 13 is of a 75 diameter to closely fit within the container.

Connecting the members 13 and 14 are wires which are formed with vertical portions 15 and downwardly extended loop portions 16 arranged throughout their lengths, 80 the loop portions 16 of adjacent wires being in alignment with each other so that dishes may be placed therein and supported in upright positions so that the water sprayed through the pipe will contact with the flat 85 surfaces of the plates or dishes supported within the container.

In order that the dish rack may be readily removed, a bail 17 is provided, the same being connected with the upper circular member 14 and so constructed that when the cover is removed, the bail may be grasped by the hands of the person using the device, and readily removed for cleaning purposes, or for adapting the device for use in cleaning 95 larger articles such as churning, bowls or the like.

The pump which is indicated by the reference character 18 is supported exteriorly of the container 5 and has communication 100 with the container 5, through the extension 19, which provides a valve housing for the check valves 20 and 21. The valve housing 19 is divided by the wall 20' defining a passageway 21' through which fluid may pass to the valve 20, on the downstroke of the pump. As shown, the lower wall of the valve housing is spaced from the bottom 11 of the container 5, the lower wall of the valve housing 19 being indicated at 22', and defines an intake passageway 23' with the lower wall or bottom 11 of the container, so that upon the

upstroke of the pump water may be drawn into the pump to be forced into the container, upon the downstroke thereof.

Thus it will be seen that the valves are so constructed and operated on the intake stroke of the plunger of the pump 18, fluid will be drawn into the cylinder of the pump, but on the downstroke of the plunger, the fluid will be forced from the pump.

- 10 A pipe section 20 has connection with the extension 19 and affords means whereby the curved pipe section 25' may be connected with the extension 19, which pipe section 25' is provided with perforations 22 to permit the fluid to pass laterally therefrom.

Extending into the pipe section 25' is a removable vertical pipe section 23, which is also formed with a plurality of spray openings 24 disposed in spaced relation with each other and extending throughout the length thereof.

Mounted on the upper end of the pipe 23 is a spray head 25 which is also formed with spray openings 26 arranged in the under surface thereof, which spray openings direct fluid downwardly over the outer surfaces of the dishes supported within the container.

The upper end of the spray head 25 is closed to insure against water being sprayed upwardly where it would have no utility as a cleaning fluid.

The cover for the container is indicated by the numeral 27 and may be removed or positioned on the container readily.

35 A discharge opening 28 is formed in the container and is supplied with a pipe and valve construction so that the fluid in the container may be emptied after the dishes have been washed.

40 In the use of the device, the dishes to be washed are positioned on the rack in such a way that the dirty sides will be exposed to the spray passing through the spray openings

of the pipes 25' and 23. Scalding water and soap may now be placed within the container 45 and the cover positioned as shown by Figure 1.

The operator now operates the pump to force the liquid through the spray opening and onto the dishes, whereupon the water 50 cleanses the dishes.

Should it be desired to clean larger articles such as churning, bowls or the like, the dish rack may be removed and a churn such as indicated in dotted lines in Figure 1 may be 55 positioned over the spray head and the pump operated to force liquid into the churn.

I claim:

In a dish washer, a body portion, bracket members secured within the body portion 60 adjacent to the bottom thereof, a removable bottom formed of wire mesh material, supported on the bracket members and dividing the body portion into an upper and a lower compartment, a dish rack in the body portion and resting on the removable bottom, said dish rack including a lower circular member and an upper circular member, rods having loops formed therein and connecting the circular members, the loops defining recesses 65 to support dishes therein, a spraying pipe extending through the lower compartment and extending upwardly through the central portion of the body portion, said spraying pipe having openings formed throughout the 70 length thereof and adapted to spray water laterally onto dishes supported on the rack, said pipe terminating at a point adjacent to the upper end of the body portion, a nozzle 75 on the free end of the pipe for spraying water passing through the pipe, and means for drawing liquid from the lower compartment and forcing liquid through the spraying pipe.

In testimony that I claim the foregoing as my own, I have hereto affixed my signature.

JAMES WILSON LOWTHORP.
